UNITED STATES PATENT OFFICE.

CHARLES W. CARTER, OF WESTVILLE, INDIANA, ASSIGNOR TO LESTER L. BOND AND
GEORGE COATSWORTH, OF CHICAGO, ILLINOIS.

CORN-SHELLER.

Specification of Letters Patent No. 23,424, dated March 29, 1859.

To all whom it may concern:

Be it known that I, CHARLES W. CARTER, of the town of Westville, in the county of Laporte and State of Indiana, have invented 5 a new and useful Machine for Shelling Corn, called a "Corn-Sheller;" and I do hereby declare that the following is a full, clear, and exact description of the construction and operation of the same, reference being had to the annexed drawings, making a 10 part of this specification, in which—

Figure "1" is a front elevation of the same showing the crank cog wheels, &c.; Fig. "2" a side elevation with part of the 15 external truncated cone removed so as to exhibit the internal sectional cone and Fig. "3" a part of the upright shaft and one-fourth part of the internal cone which is separated from the shaft at the top to show the 20 manner of its connection and joined at the bottom showing the movable pintle and guide spring.

In the drawings "A" represents the frame of the machine, "B" hopper fastened to the 25 top of frame, "C" plate or bar across the hopper in which the head of shaft revolves, "E" center on across bar of frame at which the foot of the shaft revolves, "D" upright shaft, "G" cog wheel by which the shaft 30 D is made to revolve, "H" horizontal shaft with mitered cog wheel, "I" cog wheel by which the shaft H is made to revolve, K cog wheel on crank shaft, L crank, M mitered cog wheel by which the external cone 35 is made to revolve, "N" plate or bar across the bottom of external cone attached to the wheel M and by which the cone is held in place, "O" external truncated cone, "P" internal sectional cone, "Q" circular plate 40 on the top of shaft D in which the sections of cone P are fastened, R pins inserted in plate Q, "S" pintle, "T" holes through which the pintle S plays, "U" spring, V triangular spiral ridges on the external surface of the cone P, W similar ridges on internal surface of cone O, "a a" belt wheel 45 on crank shaft, "b b" fly wheel on shaft H.

The nature of my invention consists in 50 constructing a machine with two cones revolving in opposite directions, the internal cone P accommodating itself to the size of

the ears of corn passing through by being made in sections, which sections are hinged at the top by the hinge R or any equivalent device, held in place at the bottom by the 55 pintle S, and made to operate against the external cone O by means of a guide spring U, forming a complete machine in combination with the other parts shown and described herein.

To enable others skilled in the art to make and use my invention I will proceed to describe its construction and operation.

I construct my machine entirely of iron 60 although the frame by using a different form may be made of wood of any desired size or height. The cones O and P are about one and one-half feet in length and of any required diameter. The external cone O is made hollow with triangular ridges on the 65 inner surface. The internal cone P is made in sections of which four is the number found best in working. The sections or quarters are hinged at the top in the plate Q and are held in place at the bottom laterally 70 by the pintle S which slides in the holes T through the shaft D and are held in place centrifugally by the guide spring U which also regulates the space between the cones and adapts it to the size of the ears of corn 75 passing through. The external surface of the cone P and the internal surface of the external cone O have triangular ridges or rows of teeth upon them about four inches apart and running spirally in opposite directions.

The power is applied at the crank L or belt wheel *a a* and is communicated to the cog wheel K, from that to the cog wheel I on the shaft H with mitered cog wheel by 80 which the mitered cog wheels M and G are made to revolve (these wheels may be either mitered or plain). The wheels M and G revolve in opposite directions which produces a rapid motion without great loss of power. 85 The cog wheel G is attached to the shaft D. The cog wheel M is held in place by a pin through the shaft D immediately below it and supported by a washer. It is attached firmly to the plate or bar N both of which 90 revolve around the shaft D and the plate or bar N supports the cone O. The corn after 100

passing through the sheller may be separated from the cobs by placing any ordinary separator under the machine.

What I claim as my invention and desire to secure by Letters Patent is:

The sectional truncated cone P constructed as described with the pintle S, guide

spring U, and hinge R and arranged to operate in combination with the outer cone O in the manner and for the purposes specified. 10

CHARLES W. CARTER.
